UNITED STATES PATENT OFFICE.

WILLIAM J. KELLY, OF CLINTON, IOWA, ASSIGNOR TO KELLY MANUFACTURING CO., OF CLINTON, IOWA, A CORPORATION OF IOWA.

UPHOLSTERING CHAIR ARMS.

Application filed April 6, 1927. Serial No. 181,518.

This invention relates to improvements in upholstering chair arms, and more particularly to reinforcing means for the upholstering of chair arms of davenport and the like.

5 An object of the invention is to provide a simple and inexpensive form for use in constructing arms of overstuffed furniture, such as chairs or davenport.

10 A further object of the invention is to provide an article of the character just referred to which is capable of having one or both of its ends contracted prior to the upholstering of the article of furniture to which it is applied in order to produce an arm which is 15 narrower at one or both ends than between its ends.

Other objects will appear as the description proceeds.

In the accompanying drawings, which 20 illustrate embodiments of the invention:

Figure 1 is a perspective view of a chair embodying the invention and having an end of one arm broken away to illustrate the method of reinforcing and upholstering the 25 same;

Figure 2 is a perspective view of a form for a chair arm embodying the invention and made of two parts;

Figure 3 is a perspective view of a form for 30 a chair arm embodying the invention and made of a single part;

Figure 4 is a side elevation of my preferred form for a chair arm;

Figure 5 is a sectional view taken on the 35 line 5—5 of Figure 4; and

Figure 6 is a detail view showing a portion of a three-ply form which may be used for a chair arm where it is desired to support extra heavy strain.

40 Like characters of reference are used throughout the following specification and the accompanying drawings to designate corresponding parts.

The chair comprises a base 1, seat 2, back 3, 45 arms 4 and legs 5.

My invention deals wholly with the construction and reinforcing of the arms 4, which are so formed that the same will support any reasonable load placed upon them, 50 without bulging or breaking down.

A frame strip 6 is secured to the base 1 adjacent its lower edge, and supports the outwardly and upwardly extending form 7, which may be of paper or cardboard and 55 which conforms generally to the shape of the

arm. This form 7 has its upper end bent outwardly into substantially semi-circular form, as clearly illustrated in the several figures. A supporting brace 8 extends longitudinally of the arm 4, from its front to back 60 end, and is attached at its opposite edges to the form 7, thereby effectually reinforcing the semi-circular portion of the arm. Further reinforcing strips 9 and 10 may be secured to the brace 8 above and below the brace 65 8, the upper strip 9 contacting with the under surface of the form 7. The padding 11 is applied over the form 7, and the outer covering 12 is secured in place over the padding 11 and over the outside surface of the 70 arm. A cross section taken through the reinforcing strips 9 and 10 and the brace 8 would show a cruciform member, thus providing a reinforcing bracing member of great strength and also with sufficient surfaces for the proper 75 tacking or attaching of the form strip thereto, such strip, as shown, being composed of a number of sheets or a single sheet of a relatively stiff flexible material, so that the same may be readily bent around and attached to 80 this cruciform member. Thus it will be seen that the arm will be reinforced laterally as well as vertically, and will be capable of standing heavy loads without breaking down.

Further provision is made for narrowing 85 the upper portion of the arm, if desired, toward its front and rear ends by providing longitudinally extending inwardly tapering slits 15 at one or both ends of the curved portion of the form 7. It will be seen that the adjacent edges or sides of the slits 15 may be drawn together and suitably fastened, thereby effecting the desired narrowing of the 90 chair arm at its front and rear ends.

A slight modification of the form 7 is illustrated in Figure 2 of the drawings where the curved upper portion of the form is formed separately from the body portion thereof and is secured to the upper edge of the body portion with its inner edge underlying the latter. 95

It will be observed from Figure 6, that the form 7 can also be made of laminated strips, which construction will materially add to the strength and rigidity of the same.

Many minor changes in detail of construction may be restored to without departure 105 from the spirit of the invention.

I claim:

1. An arm for davenport and the like comprising a form made from a sheet of rela- 110

tively stiff flexible material and curved outwardly and downwardly at its upper end, a cruciform brace extending longitudinally of and within said curved portion of said form 5 and attached throughout its length thereto, a padding superimposed on said form, and a cover for said padding.

2. An arm for davenport's and the like comprising a form made from a sheet of relatively stiff flexible material and substantially 10 semi-circular in cross-section at its upper end, a brace extending substantially in a horizontal plane longitudinally of said curved portion of said form and attached at its opposite 15 sides thereto, a longitudinally disposed reinforcing strip interposed between said brace and said semi-circular portion of said form and attached to said brace and form, a padding superimposed on said form, and a covering 20 for said padding.

3. An arm for davenport's and the like comprising a form made from a sheet of relatively stiff flexible material and curved outwardly and downwardly at its upper end and 25 provided with longitudinally disposed slits in its end edges whereby the same may assume a contracted curvature, a brace extending longitudinally of said curved portion of said form and attached at its opposite sides 30 thereto, a padding superimposed on said form, and a cover for said padding.

4. A form for overstuffed furniture arms, including a sheet of relatively stiff flexible material, the upper end of which is curved

outwardly, and a reinforcement for said 35 curved end consisting of a longitudinal strip attached at one edge to the body of the sheet and at the opposite edge to the extreme curved end of the sheet.

5. A form for overstuffed furniture arms, 40 including a sheet of relatively stiff flexible material, the upper end of which is curved outwardly, a reinforcement for said curved end consisting of a longitudinal strip attached at one edge to the body of the sheet and at the opposite edge to the extreme curved 45 end of the sheet, and two strips extending longitudinally of the last strip, one above said strip and having its edge attached to the inner curved face of the sheet and the other projecting below said strip to form a brace and tacking member for the covering 50 of the arm.

6. A form for the arms of overstuffed furniture, comprising a sheet of stiff material having its upper edge bent outwardly into substantially semi-cylindrical form and having one end of said substantially semi-cylindrical portion longitudinally slitted whereby 55 the diameter of said slitted part may be reduced toward said end, and a strip extending longitudinally of said substantially semi-cylindrical portion approximately diametrically thereof and having its opposite edges 60 secured to said portion.

In testimony whereof I have hereunto set my hand.

WILLIAM J. KELLY.
